UNITED STATES PATENT OFFICE.

WILLIAM C. DEE, OF CLEVELAND, OHIO, ASSIGNOR TO THE ENGELN ELECTRIC COMPANY, OF CLEVELAND, OHIO, A CORPORATION OF OHIO.

ELECTRICAL APPARATUS.

Application filed September 19, 1918. Serial No. 254,780.

To all whom it may concern:

Be it known that I, WILLIAM C. DEE, a citizen of the United States, residing at Cleveland, in the county of Cuyahoga and 5 State of Ohio, have invented certain new and useful Improvements in Electrical Apparatus, of which the following is a specification.

This invention relates to electrical apparatus, and more particularly to apparatus designed for the use of X-rays in dental and other work.

The object of the invention is to provide improved apparatus for taking X-ray 15 photographs of teeth, and which apparatus enables the X-ray tube to be readily swung into the most convenient position for application of the rays to any desired tooth and then traversed over an orbit so as to bring 20 within working range each and every tooth in the jaw, or other part to be exposed. Another object of the invention is to provide apparatus of this kind carrying a support for the X-ray tube provided with a number 25 of friction joints so that the tube can be brought to and held frictionally in any desired position, and which also enables the line or direction of application of the rays to be adjusted to almost any angle or direction. 30

A further object of the invention is to provide apparatus of this kind in which the patient is protected from the possibility of injury by stray discharges of high tension 35 current by so arranging the apparatus that a grounded portion thereof is always interposed between the high tension lead wire and the patient, whatever be the position to which the tube is adjusted. A further 40 object of the invention is to generally simplify and improve the apparatus in a manner to reduce its cost and thoroughly insulate and protect all of the electrical circuit wires.

Further objects of the invention are in 45 part obvious and in part will appear more in detail hereinafter.

In the drawings, which represent one suitable embodiment of the invention, Fig. 1 50 is a side elevation; Fig. 2 is a sectional elevation, on a larger scale, through the upper portion of the post or standard and a part of the hinged arm; Fig. 3 is a side elevation, partly broken out and in section, of 55 the outer end of the hinged arm; Fig. 4 is

a detail cross section on the line 4—4, Fig. 3; Fig. 5 is a detail cross section on the line 5—5, Fig. 1; Fig. 6 is a detail view, partly in section, illustrating the joints between the X-ray tube and the goose neck arm; 60 and Fig. 7 is a view, partly in elevation and partly in section on the line 7—7, Fig. 2, illustrating a hinge joint.

The apparatus shown in the drawings comprises a suitable base or support 1 which, 65 with its contents, is heavy enough to stabilize the entire apparatus and permit the X-ray tube to be adjusted to any position without liability of tipping over the apparatus. This base usually contains the necessary trans- 70 formers and other devices for producing and controlling the X-rays, and which need not be described in detail as they form no part of the present invention. 2 represents a tubular column rising from the base 1 and 75 rigidly attached thereto. Within the upper end of this column is located the tubular shank 3 of one member 5 of a hinge, said shank having an annular shoulder 4 resting upon the upper edge of the column and thereby serving to support the hinge on the same but nevertheless permitting the hinge and the shank 3 to be turned around in the column, whereby the entire X-ray tube supporting arm can be swung around a vertical 80 axis through the center of the column 2. This arrangement enables the apparatus to be practically permanently located at one side of the dentist's chair and the X-ray tube normally kept back out of the way but ready 85 to be swung out into operative position whenever desired. The base 1 can, however, be provided with rollers or casters to enable it to be moved over the floor, if desired. 90

The hinge member 5 before referred to 95 operates with a hinge member 6 carrying two hollow bosses 7 and 8 whose purpose will appear. Member 5 is bifurcated to form two parallel disc members 9, while member 6 is also bifurcated to form discs 10 which 100 are spaced apart and which fit between the discs 9. The two sets of discs are pivotally connected by aligned bolts 11, which form a hinge axis, and one of which is provided with a handle 11^a for tightening it against a friction washer 12. By screwing up the bolt friction may be produced in the joint so that the hinge members will remain in practically any position to which they are 105 adjusted. To insulate the metal parts and 110

protect the lead wires the discs 10 are preferably faced with insulating discs 13 held thereto by screws 14.

If desired, the hinge member 5 may be provided with a lateral projection 15 to which is secured a tube or casing 16 extending down the back of the column 2 and which serves to enclose a pressure spring 17. Said spring at its upper end abuts a shoulder on the member 15 and at its lower end engages an abutment 18 adjustably threaded upon the lower end of a rod 19 whose upper end is connected by a chain, cable or link 20 to the member 6. The abutment 18 extends outwardly beyond the tube 16 so that it can be conveniently adjusted by the fingers. Spring 17 exerts a constant tendency to pull down the rod 19 and thereby elevate the X-ray carrying arm, so that it serves as a counter-weight for said arm and enables it to be more easily adjusted.

The hinge member 6 serves as a support for the main X-ray tube carrying arm, which is in the form of a metal tube or pipe 22 held rigidly at one end in the boss 7 and which is curved outwardly and downwardly, as shown in Fig. 1, so that its outer end depends practically vertically. By swinging the arm 22 in its vertical plane of movement about the axis of hinge 5, 6, the outer end of arm 22 may be more or less inclined to the vertical, as desired. Tube 22 serves as the casing for the high tension conductor and also supports, such as by the bridges 23, a smaller metal tube 24 which incloses another set of lead wires to be described. This latter tube is inserted in the hollow boss 8 before referred to and terminates at its opposite end short of the end of the arm 22.

At its outer end the tubular arm 22 has rigidly secured thereto a thimble 25 into the lower end of which is threaded a hollow tubular member 26 formed of suitable insulating material. This thimble also serves as a bearing support for a hinge joint carrying an auxiliary goose neck arm. As illustrated in Fig. 4, said joint comprises two members 27 and 28, of which member 27 has a sleeve bearing portion 29 embracing the bearing thimble 25 and held thereon by a nut 30. Sleeve 29 is split at 31 and the two ears thereof may be clamped together by the thumb screws 32 so as to adjust the friction in the bearing to an amount sufficient to hold the parts in any desired adjusted position. Member 27 is also pierced to receive a thumb screw 33 threaded into a friction disc 34 having dowel pins 35 working in recesses in member 27. This member 34 has an annular flange 36 which fits in a circular recess in the member 28, so that the screw 33 not only serves as a hinge pin for the joint but also enables the friction in the joint to be readily adjusted. Member 28 is also provided with a cylindrical portion 37 to which

is rigidly secured one end of the tubular auxiliary goose neck arm 38 which, as shown in Fig. 1, is bent back and forth into practically S form, and which is connected by a hinge joint to a bracket for supporting the X-ray tube. If desired, a suitable counter-balancing device, such as the spring form used for the main arm, may be employed to counterbalance the auxiliary arm on the main arm. The opposite end of the tubular goose neck arm 38, as illustrated in Fig. 6, is connected to a hinge joint member 40 connected to a member 41. The joint between members 40 and 41 need not be described in detail as it is similar in all respects to the joint shown in Fig. 4, it being sufficient to state that member 40 is of the same form as member 28 and member 41 corresponds to the member 27.

Member 41 is enlarged to form a disc 42 fitting a circular socket in member 43 and held therein by a bolt 44, which serves as a hinge axis. Member 43 surrounds the disc 42 and is split at one side, as at 45, the two ears being connected by a screw 46 by means of which the friction in the joint can be varied.

Member 43 has connected thereto a plate 47 having an opening through which the cylindrical shank 48 of one member of the X-ray tube or shield is inserted, said plate also having openings to receive several curved rods or wires 49, say three, connected at their opposite ends to a ring 50 surrounding another portion of the X-ray tube or shield. The rods 49 also carry the thumb nuts 51. As will appear from Fig. 1, these thumb nuts can be removed to release the wires so that the X-ray tube and shield can be inserted or removed from the frame as desired.

From the construction described it will be observed that the X-ray tube can be adjusted to an infinite variety of positions, due to the fact that said tube is mounted to have turning adjustment around six separate axes inclined at various angles to each other. The turning movement of arm 22 around the vertical axis of column 2 enables the lamp to be brought generally into range of the patient, who is seated so that his head lies practically under the outer depending end of arm 22. By adjusting the arm 22 upwardly or downwardly in a vertical plane, around the axis of the hinge 5, 6, the axis of the bearing at the outer end of arm 22 may be inclined to the vertical or to a position substantially perpendicular to the slant of the jaw. When the X-ray tube is then adjusted to the proper position on the auxiliary arm, it can be swung around through an orbit in the plane of the jaw so as to come successively into operative relation with the several teeth in the jaw, and with the angle of application of the rays inclined

at the proper angle to the slanted front upper teeth and inclined at a different but yet proper angle to the more nearly vertical side upper teeth, and without requiring a 5 separate setting of all of the joints for each different tooth. The adjustment of the auxiliary arm at the hinge joint 27, 28 and of the X-ray tube at the joint 40, 41 enable the X-ray tube to be adjusted to the proper 10 angular relation to the teeth while still maintaining the X-ray tube at the proper distance from the teeth. The hinge joint 40, 41 at the outer end of the auxiliary arm enables the lamp to be adjusted to the proper 15 inclination to the horizontal, and the hinge joint 42, 43 enables the lamp to be given an askew position for special conditions. By calling into play the proper ones of these various joints and properly seating the 20 patient, it is possible not only to correctly produce an exposure of any tooth but to also by a simple turning movement, traverse either entire jaw and successively expose each tooth therein.

25 That portion of the goose neck arm 38 which lies substantially horizontal and which crosses the axis of the sleeve 29, and which is marked A, in Fig. 1, serves as a convenient hand grip for manipulation of 30 the apparatus. By grasping the manipulating part A with one hand and the shank 48 or some other part of the X-ray tube with the other hand all necessary adjustments of the apparatus can be readily made. By 35 holding the part A stationary the tube can be adjusted relative to arm 38, while by pushing or pulling in the proper direction on the part A the main arm 22 can be raised or lowered and by twisting said manipulating part A the necessary adjustments around the axis of the sleeve 29 can be readily made.

40 Referring now to Fig. 2, 52 represents the high tension conductor from the transformer in the base 1 of the apparatus. This conductor includes a central metal rod 53 surrounded by thick layers of insulation 54. The upper end of said conductor is connected by a suitable elastic joint to a conductor 55 which runs to the X-ray tube. As 45 shown, rod 53 is closely hugged by a compression spring 56 whose upper end abuts a contact 57 electrically connected to the wire in the center of cable 55, which, of course, is heavily insulated. This cable runs through the cavity between the discs 14, thence through the tubular arm 22 to the insulated sleeve 26. The cables 52 and 55 are surrounded by insulation, for example, by 50 gum rubber inclosed in a micanite tube 58. The arrangement shown in Fig. 2 permits the upper portion of the cable, marked 55, to move slightly up and down as the arm 22 is adjusted vertically to various positions.

55 On the outer end of the insulated tube 26 is a post 59 carrying a spring wound pulley

or wheel 60 and a bracket 70 carrying an eye 71. On the wheel 60 is coiled a fine insulated wire 72, one end of which is electrically connected through the post 59 to the wire center of cable 55. This fine wire is led 70 through the eye 71, thence through an eye in a post 73 having a suitable flexible resilient connection, such as a loose spring connection 74 to the goose neck arm 38, and thence to the terminal 75 of the X-ray tube. 75 It will, of course, be understood that the other high tension terminal of the X-ray tube is suitably grounded to a metallic portion of the frame, preferably at the outer end of the arm 38. This arrangement perfectly 80 protects the patient against stray high tension discharges, because the form of the goose neck arm 38 is such that said arm is always interposed between the patient and the high tension wire 72, so that brush discharges from this wire are grounded to the frame before they reach the patient. As the arm 38 is adjusted relative to the arm 22, or as the X-ray tube is adjusted relative to arm 38, the wire 72 is wound up upon or is paid 85 out from the pulley 60, and the post 73, because of its spring support 74, bends to the right or left, so as to always keep the wire 72 a sufficient distance away from the metallic portion of the frame.

90 In this apparatus, the X-ray tube is usually a Coolidge tube or other similar tube in which the quantity of X-rays is regulated by varying the temperature of the cathode filament, said filament being a tungsten spiral or other suitable device through which heating current at low voltage is passed. 95 76 represents the connection for leading heating current to the cathode filament. The wires 77 for leading current thereto pass through a tube 78 in the column 100 2 and located outside of the micanite tube 58, and which is preferably grounded to protect the low tension current from static effects. From the tube 78 these wires are led to and through the tube 24 and thence through the goose neck arm 38, so that for the most part they are concealed but are exposed where necessary because of the flexibility of a joint.

110 115 The arrangement described is simple and highly efficient in that it enables the X-ray tube to be located and supported in any position at exactly the proper angle.

120 What I claim is:

1. Apparatus for use in dental radiography comprising a support, a main arm pivoted thereto on a horizontal axis and having a bearing portion at its outer end, the longitudinal axis of which by tilting movement of said arm may be adjusted to various positions inclined to the vertical, a second arm rotatable around the axis of said bearing portion and having a manipulating portion crossing said axis, and an X-ray tube 125 130

supporting frame carried by said arm, and electric connections therefor.

2. Apparatus for use in dental radiography comprising a support, a main arm pivoted thereto on a horizontal axis and having a bearing portion at its outer end, the longitudinal axis of which by tilting movement of said arm may be adjusted to various positions inclined to the vertical, a second arm rotatable around the axis of said bearing portion and having a manipulating portion crossing said axis, an X-ray tube supporting frame carried by said second arm, and electric connections therefor including a high tension conductor on the opposite side of said arms from the position of the patient.

3. Apparatus for use in dental radiography, comprising a frame including a main arm having a depending bearing portion adjustable in a vertical plane to different levels and with varying inclinations of the bearing axis to the vertical, and an auxiliary arm swiveled around the bearing portion of the main arm and extending across the axis of said bearing and at its outer end provided with means for supporting an X-ray tube, the adjustment of said bearing portion serving to locate the X-ray tube with reference to either jaw, and the swiveling motion of said auxiliary arm enabling the X-ray tube to be moved through a symmetrical orbit about the jaw.

4. Apparatus for use in dental radiography, comprising a frame including a main arm having a depending bearing portion adjustable in a vertical plane to different levels and with varying inclinations of the bearing axis to the vertical, and an auxiliary arm swiveled around the bearing portion of the main arm and extending across the axis of said bearing and at its outer end provided with means for supporting an X-ray tube, the adjustment of said bearing portion serving to locate the X-ray tube with reference to either jaw, and the swiveling motion of said auxiliary arm enabling the X-ray tube to be moved through a symmetrical orbit about the jaw, the supporting means for said X-ray tube being constructed and arranged to enable said tube to be adjusted on said auxiliary arm in a vertical plane to any angular position relative to the long axis of a tooth.

5. Apparatus for use in dental radiography, comprising a support, a main arm pivoted thereto on a horizontal axis and having a bearing portion near its outer end, the longitudinal axis of which by tilting movement of said arm may be adjusted to a vertical position or to various positions inclined to the vertical, an auxiliary arm rotatable around said axis on said bearing portion and having a manipulating portion crossing said axis, and an X-ray tube sup-

porting frame carried by said auxiliary arm.

6. Apparatus for use in dental radiography, comprising a support, a main arm pivoted thereto on a horizontal axis and having a bearing portion near its outer end, the longitudinal axis of which by tilting movement of said arm may be adjusted to a vertical position or to various positions inclined to the vertical, an auxiliary arm rotatable around said axis on said bearing portion and having a manipulating portion crossing said axis, and an X-ray tube supporting frame carried by said auxiliary arm and mounted thereon to have swinging movement in a vertical plane.

7. Apparatus for use in dental radiography, comprising a relatively heavy base adapted to rest upon the floor and provided with a column, a main arm pivoted to the upper end of said column to swing in a vertical plane and having a bearing portion near its outer end, the longitudinal axis of which by tilting movement of said arm may be adjusted to a vertical position or to various positions inclined to the vertical, an auxiliary arm rotatable around said axis on said bearing portion and having a manipulating portion crossing said axis, and an X-ray tube carried by said auxiliary arm.

8. Apparatus of the class described, comprising a column, a main arm extending outwardly therefrom and pivoted thereto to swing in a vertical plane, the outer end of said main arm having a depending bearing portion whose axis may be inclined to the vertical by swinging movement of said main arm on said column, a sleeve swiveled upon said bearing portion, an auxiliary arm having a hinge connection on a horizontal axis with said sleeve between the opposite ends of said main arm, said auxiliary arm extending downwardly and outwardly and crossing the axis of said bearing, and means at the outer end of said auxiliary arm for supporting an X-ray tube.

9. Apparatus of the class described, comprising a column, a main arm extending outwardly therefrom and pivoted thereto to swing in a vertical plane, the outer end of said main arm having a depending bearing portion whose axis may be inclined to the vertical by swinging movement of said main arm on said column, a sleeve swiveled upon said bearing portion, an auxiliary arm having a hinge connection on a horizontal axis with said sleeve between the opposite ends of said main arm, said auxiliary arm extending downwardly and outwardly and crossing the axis of said bearing, and means at the outer end of said auxiliary arm for supporting an X-ray tube and for adjusting the same to any angular position relative to said axis.

10. Apparatus of the class described, comprising a column, a main arm extending outwardly therefrom and pivoted thereto to swing in a vertical plane, the outer 5 end of said main arm having a depending bearing portion whose axis may be inclined to the vertical by swinging movement of said main arm on said column, an auxiliary arm swiveled to the bearing portion of 10 said main arm and extending downwardly and outwardly from said column, means for supporting an X-ray tube upon the outer end of said auxiliary arm, said main and auxiliary arms forming a ground return 15 circuit for the high tension circuit to said X-ray tube, and said main arm forming a conduit for the high tension lead to said X-ray tube, and means for supporting a lead wire for said X-ray tube on the far 20 side of said auxiliary arm from said column.

11. Apparatus of the class described, comprising a column, a main arm extending outwardly therefrom and pivoted thereto to swing in a vertical plane, the outer 25 end of said main arm having a depending bearing portion whose axis may be inclined to the vertical by swinging movement of said main arm on said column, an auxiliary arm swiveled to the bearing 30 portion of said main arm and extending downwardly and outwardly from said

column, means for supporting an X-ray tube upon the outer end of said auxiliary arm, said main and auxiliary arms forming a ground return 35 circuit for the high tension circuit to said X-ray tube, and said main arm forming a conduit for the high tension lead to said auxiliary tube, and means for supporting a lead wire for said X-ray tube on the far side of said auxiliary arm from 40 said column and spaced from said auxiliary arm.

12. Apparatus for use in dental radiography, comprising a frame including a main arm having a depending bearing portion located near its one end and adjustable in a vertical plane to different levels and with varying inclinations of the bearing axis to the vertical, and an auxiliary arm swiveled around the bearing portion of the 45 main arm and provided at its outer end with means for supporting an X-ray tube, an electric conductor for said X-ray tube having a portion spaced from said frame, and means located on said main arm and 50 below said bearing for automatically taking up slack in said conductor as the X-ray tube is adjusted to its various positions.

In testimony whereof I affix my signature.

WILLIAM C. DEE.
